MILK BOTTLE CAP REMOVER

Filed Sept. 18, 1928

Inventor
Ocelia H. Parry

By *Watson E. Coleman*,
Attorney

UNITED STATES PATENT OFFICE.

OTELIA H. PARRY, OF LONG BEACH, CALIFORNIA.

MILK-BOTTLE-CAP REMOVER.

Application filed September 18, 1928. Serial No. 306,659.

This invention relates to a milk bottle cap remover and has for its primary object to provide an article of this character which will be positive in action and which will enable one to completely remove a bottle cap without the necessity of touching the same with the fingers.

Another object of the invention is to provide a bottle cap remover of such construction that the cap penetrating member thereof will be swung toward the cap to enter the same obliquely to the surface, thus insuring the quick and smooth penetration of the cap without bending or breaking the same.

Other objects and advantages of this invention will become apparent as the description of the same proceeds and the invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a vertical sectional view of the upper portion of the milk bottle showing the cap removing device embodying the present invention in operative position.

Figure 2 is a top plan view of the structure;

Figure 3 is a vertical sectional view through the upper portion of the bottle taken in a plane at right angles to the section of Figure 1;

Figure 4 is a sectional view through the bottle and through the cap removing structure showing in dotted lines the manner of operation of the device.

Referring to the drawing in detail, it will be seen that the present invention comprises a disk like plate 1 having formed therethrough an elongated recess or opening 2.

Secured to one face of the disk 1 is a plate 3, the central portion of which is formed to provide a hood 4, this hood overlying the major portion of the opening 2. The hood structure 4 consists of a top wall 5 which curves from a relatively high point with respect to the plate 1, downwardly to the plate 3 from which it is formed, the side walls 6 closing the hood 4 at each side in the manner

shown. It will thus be seen that the hood is open only at one end and that the opening through the plate 1 extends slightly beyond the open end of the hood.

Each of the side walls 6 of the hood 4 has a bearing opening 7 formed therethrough in each of which is engaged the inturned free end portion 8 of a leg of substantially U-shaped pin carrier body 9.

The body 9 is secured at the central portion of the top or yoke thereof to an elongated cap penetrating pin 10. One end of this pin is sharpened as indicated at 11 while the opposite end has a finger ring 12 formed thereon through which the operator of the device may engage a finger.

When the pin holder 9 is in substantially upright position, the pin 10 will be arranged at an angle over the plate 1 and the penetrating point thereof, which is slightly curved as shown, extends downwardly across the open end of the hood 4 and is directed toward the opening 2 formed through the plate. It will be readily seen that upon swinging the ring end of the pin 10 in one direction the pointed end of the pin will swing downwardly toward and enter the surface of a milk bottle cap lying beneath the plate 1 at an acute angle thereto.

In order to hold the inturned portions 8 of the legs of the member 9 in position in the bearing apertures 7, there is provided a resilient metal tongue 13, one end of which is engaged between the lowest part of the top 5 of the hood and the plate 1, while the other or forward end extends forwardly in the hood to engage between the top thereof and the flange 5', formed along the front edge thereof. The tongue is of substantially the same width as the interior of the hood, and is designed to overlie the ends 8 of the legs of the yoke 9, pressing downwardly thereon and assisting the yoke in its swinging movement. It will thus be seen that the spring holds the turned ends of the legs of the member 9 securely against loose movement in the bearing openings.

When the plate 1 has been placed in position in the mouth of the milk bottle, over the usual cap 14', the bottle being here indicated by the numeral 14, it is secured against slipping by a slightly curved resilient strap member 15. This strap member has one end secured to the rear face of the pin supporting body or yoke 9, as indicated at 16, while the other end thereof is rolled under as in

dicated at 17, for engagement over the usual rolled edge of the bottle mouth.

As the ring end of the pin 10 is swung over to cause the pointed end 11 to penetrate the bottle cap, the resilient strap is straightened out until the strain thereon becomes sufficient to cause the turned end 17 to slip its connection with the edge of the bottle mouth.

The penetrating or pointed end 11 of the pin 10 is preferably formed to present two oppositely positioned sharpened edges throughout a distance of approximately one inch of its length to further insure its easy penetration of the bottle cap.

Secured at diametrically opposite points to the plate 1, are the ends of a handle or bail 18. This bail is provided for the convenient lifting of the plate or for hanging the same when not in use.

From the foregoing, it will be readily seen that with a bottle cap removing device of this character the cap can be quickly and easily taken from the bottle mouth without being bent or broken and without the necessity of touching it with the fingers.

Having thus described my invention what I claim is:—

1. A bottle cap removing device comprising an apertured base plate, an inverted U-shaped yoke member pivotally mounted upon the plate over the aperture thereof, a pointed pin member mounted intermediate its ends upon said yoke at the center thereof and designed to have the pointed end thereof swung downwardly to extend through said aperture when the supporting yoke is oscillated, and a resilient member assisting the working movement of the yoke.

2. A bottle cap removing device comprising an apertured base plate, a yoke member pivotally mounted upon the plate over the aperture thereof, a pointed pin member carried intermediate its ends by said yoke and designed to have the pointed end thereof swung downwardly to extend through said aperture when the supporting yoke is oscillated, and means carried by the plate for covering the major portion of the aperture thereof, said pointed pin end swinging under the covering when in use.

3. A milk bottle cap remover comprising an apertured plate member designed to be positioned over a cap, a hood overlying the aperture of the plate, a substantially U-shaped yoke member straddling said hood and mounted for oscillatory movement thereover, and a pointed cap penetrating pin carried by the yoke and designed to have the pointed end thereof extended downwardly

under the hood and through said aperture when the yoke is oscillated to penetrate a bottle cap lying beneath the plate.

4. A milk bottle cap remover comprising an apertured plate member designed to be positioned over a cap, a hood overlying the aperture of the plate, a substantially U-shaped yoke member straddling said hood and mounted for oscillatory movement thereover, a pointed cap penetrating pin carried by the yoke and designed to have the pointed end thereof extended downwardly under the hood and through said aperture when the yoke is oscillated to penetrate a bottle cap lying beneath the plate, and resilient means within the hood acting upon the pin point to assist it in the penetration of a bottle cap.

5. A milk bottle cap remover comprising an apertured plate member designed to be positioned over a cap, a hood overlying the aperture of the plate, a substantially U-shaped yoke member straddling said hood and mounted for oscillatory movement thereover, a pointed cap penetrating pin carried by the yoke and designed to have the pointed end thereof extended downwardly under the hood and through said aperture when the yoke is oscillated to penetrate a bottle cap lying beneath the plate, and a resilient holding member normally connecting said pin carrying yoke with an adjacent bottle lip throughout the major portion of the period of movement of the yoke when the same is being swung to cause the pin to penetrate an underlying bottle cap.

6. A milk bottle cap remover comprising an apertured plate member designed to be positioned over a cap, a hood overlying the aperture of the plate, a substantially U-shaped yoke member straddling said hood and mounted for oscillatory movement thereover, a pointed cap penetrating pin carried by the yoke and designed to have the pointed end thereof extended downwardly under the hood and through said aperture when the yoke is oscillated to penetrate a bottle cap lying beneath the plate, resilient means within the hood acting upon the pin point to assist it in the penetration of a bottle cap, and a resilient holding member normally connecting the pin carrying yoke with an adjacent bottle lip throughout the major portion of the period of movement of the yoke when the same is being swung to cause the pin to penetrate an underlying bottle cap.

In testimony whereof I hereunto affix my signature.

OTELIA H. PARRY.
